[57] **CLAIM**

The ornamental design for a power head for a vegetation cutter, as shown and described.

DESCRIPTION

FIG. 1 is a perspective view of a power head for a vegetation cutter showing our new design, with the broken line showing of the shaft and cutter portion being for illustrative purposes only and forming no part of the claimed design;

FIG. 2 is an enlarged perspective view thereof as seen from the front and one side;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top view thereof shown slightly in perspective; and

FIG. 8 is a bottom view thereof shown slightly in perspective.

FIG. 3

FIG. 5
